HOLDER FOR BOTTLES OR THE LIKE

Bette C. Graham, 6055 Woodland Drive,
Dallas, Tex. 75225

Filed May 21, 1968, Ser. No. 12,028

Term of patent 14 years

Int. Cl. D9—99

U.S. Cl. D9—176

Fig. 1

Fig. 2

Fig. 3

Fig. 4

Fig. 5

Fig. 6

FIG. 1 is a front elevational view of a holder for bottles or the like, embodying my new design;

FIG. 2 is a rear elevational view;

FIG. 3 is a top plan view;

FIG. 4 is a bottom plan view;

FIG. 5 is a view looking from the left of FIG. 1; and

FIG. 6 is a view looking from the right of FIG. 1.

The broken line showing of two bottles in FIG. 1 is for illustrative purposes only.

I claim:

The ornamental design for a holder for bottles or the like, substantially as shown and described.
